The ornamental design for a motorcycle and/or all terrain vehicle clutch basket, as shown and described.

DESCRIPTION

FIG. 1 is a perspective view of a motorcycle and/or all terrain vehicle clutch basket showing our new design;

FIG. 2 is a front elevational view thereof;

FIG. 3 is a right side elevational view, the left side, top side, and bottom side being an identical image thereof; and,

FIG. 4 is a back elevational view thereof.

The broken lines are shown for illustrative purposes only and form no part of the claimed design.
